(57) **CLAIM**

The ornamental design for a bracelet box, as shown and described.

DESCRIPTION

FIG. 1 is a front perspective view of a bracelet box, showing my new design;

FIG. 2 is a rear perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a rear perspective view of the bracelet box in an alternate configuration thereof; and,

FIG. 10 is a front perspective view thereof.

The broken lines shown in the drawings depict portions of the bracelet box that form no part of the claimed design.
